FILING DEVICE AND METHOD OF
MAKING THE SAMELe Roi E. Hutchings, Tonawanda, N. Y., assignor
to Remington Rand Inc., Buffalo, N. Y.Original application April 17, 1926, Serial No.
102,655. Divided and this application February
17, 1931, Serial No. 516,445

2 Claims. (Cl. 95—5)

This application is a division of my copending application, Serial No. 102,655, filed April 17, 1926, matured into Patent No. 1,919,433 of July 25, 1933.

5 This invention relates to filing devices in which matter to be filed is imprinted on sensitized sheets by photographic means and is then used for filing.

10 It further relates to the method of and apparatus for preparing the filing devices.

In the filing of big records, such as the record of books in large libraries, etc., considerable space is required for the record cards when the ordinary method of cards on edge in trays is used. Furthermore, the use of the files is a slow and cumbersome task especially as only one card can be seen at a time. The space required for files is also augmented by the fact that often the notation only covers a portion of the card and the balance of the card is left blank. Usually the cards are written with the large type of a typewriter whereas a much smaller type would suffice especially since only an occasional reference is made to any particular card. Sometimes it is found desirable to make duplicate record cards as when the old system of filing is to be replaced by a more efficient one. However, a large number of the library file cards are often written in unusual foreign languages so that the cost of copying them by ordinary methods would be prohibitive.

In the making of file copies of correspondence, it often happens that a considerable number of copies are needed to send to different people. However, in the last one or two carbon copies, the writing is blurred and indistinct so that rewriting becomes necessary. Also in making several carbon copies, when an error is made on the typewriter, it is both inconvenient and inefficient to make erasures on all copies and often corrections are not made on all copies, with a chance of causing serious errors because all copies are not alike.

45 An object of this invention, therefore, is to provide means for reproducing and filing voluminous records which will be highly economical for the filing space required, and very fast and convenient for reference.

50 Another object of the invention is to provide means for making an indefinite number of small sized copies of matter to be filed, by making small photographs of the matter and retaining these copies in the pockets or trays of a filing device so that several photographs will be visible

at a glance, thus greatly facilitating and speeding up reference to the file cards.

A further object of this invention is to provide means for conveniently photographing material to be filed, on sensitized paper which is in 5 roll form, the strip of sensitized paper being perforated automatically as it is exposed so that the photographs can later be severed one from the other after development and then attached together in chain form in overlapping position 10 convenient for filing.

A still further object of the invention is to provide means for copying printed matter cheaply and accurately so that all copies will be exactly alike and of equal quality, regardless of the language used; also to improve filing methods and devices in other respects hereinafter specified and claimed.

In the drawings:

Fig. 1 is a perspective view of a file tray having 20 pockets containing improved filing cards,

Fig. 2 is a front view of one of the improved file cards ready to be installed in the file pocket.

Fig. 3 is a fragmentary front view of a strip of the improved file cards after developing the 35 sensitized paper and before severing the cards one from the other,

Fig. 4 is a fragmentary front view on a large scale, of a pair of the cards joined together in overlapping position to form a chain or series of 30 cards,

Fig. 5 is a front view of one of the pockets which is adapted to support the photographic cards in filing position,

Fig. 6 is a rear view of one of the pockets with several of the photographic cards in position,

Fig. 7 is a fragmentary detail view on a large scale of the top of one of the pockets and photographic file cards,

Fig. 8 is a longitudinal sectional view through 40 one of the trays which supports the pocket frames and pockets,

Fig. 9 is a fragmentary transverse sectional view through one of the file trays,

Fig. 10 is a vertical sectional view through an 45 improved apparatus for making the photostat file cards in strip form.

Fig. 20 is a sectional elevation through the drive pulley.

20 In carrying out my invention, a specially sensitized paper 20, similar to photostat paper, is provided in strips which are rolled up to form rolls 21. This sensitized paper is used in a photographing apparatus to be hereinafter described in such a way that material such as library cards, 25 correspondence, etc., is photographed or imprinted successively on the strip of sensitized paper. Preferably at the same time that the image of the material to be copied is imprinted on the sensitized paper, various slots 22 and 23 are punched in the sensitized paper and also 30 openings 24 to form ears or tabs 25.

35 After exposure of the sensitized strip and the punching thereof, the roll of exposed sensitized paper is removed from the apparatus and developed in the usual way. The resulting strip of photographic file cards shown in Fig. 3, then is severed across dotted line 26 to form individual finished file cards 27 as shown in Fig. 2. These file cards are preferably smaller than the 40 original from which they were photographed, so that they occupy a very small space. If some of the printing has been reduced to such a small scale in photographing that it can not be easily read with the naked eye, it is contemplated to 45 employ an ordinary reading glass so that the inscriptions and reading matter 28 can be clearly seen.

50 It should be understood that these photographic file cards may be placed on edge in a file tray in the usual manner without linking the cards one to the other. However, the preferred form of the invention contemplates the use of the photographic file cards linked together to form a chain or series of cards so that a considerable 55 number of cards can be seen at a glance thus making the filing system very fast and efficient and the labor required in reference work is reduced to a minimum. The linking of the cards together to form a chain or series is accomplished by inserting the tab 25 of one card in a slot 22 of another card, then bending the upper edge of the card and inserting the opposite tab 25 in the opposite slot 22 of the adjacent card. Upon release of the card, it flattens out and the two cards are then linked together as shown in Fig. 4. This operation is 60 repeated until a chain or series of cards 29 is formed, each card overlapping the card next to it. When it is desired to remove a card from the chain, this operation is reversed and a new card can then be inserted in its place. Thus a 65 file having these chains of cards can be easily kept up to date by quickly inserting new cards to replace old ones. In some cases the notations imprinted on the photographic file card 70

75 will be so brief that only the upper part of the card will be filled with inscriptions 28. In order to use the filing system in the most efficient way, it is preferred to have a plurality of slots 22 and 23 so that the tabs of the adjacent card can be inserted in the appropriate pair of slots, thus exposing to view only the portion of the card actually containing inscriptions 28 while the blank part of the card is covered up by the adjacent card.

10

These chains of photographic file cards may be supported in any one of a variety of filing cabinets of different form so as to be readily accessible for reference. In the preferred form of filing cabinet, a pocket 30 is provided of reasonably strong material such as heavy paper, cardboard or the like. This pocket 30 has a transparent sheath 31 folded over the top edge so that the fold 32 on the front of the pocket is somewhat longer than the fold 33 on the back 20 of the pocket. This sheath is preferably secured to the pocket 30 by staples 34 although any other form of fastening device for the sheath may be used. At the bottom of the pocket 30, a semi-flexible strip 35 is preferably attached by 25 means of staples 36 so that each end of the strip 35 extends beyond the pocket 30, thus forming tongues 37.

30 A series of perforated slots 37A is provided in the pocket 30 to form a bend line so that 30 said pocket may be bent back upon itself along this bend line. The strip and pocket may then be bent somewhat in the middle, and the tongues 37 slipped under retaining angle clips 38 extending along each edge of frames 39. When the 35 pocket is then allowed to flatten out, the strips and pockets are held in alignment with the strips 35 in abutting position, edge to edge, and the upper edges of the pockets overlapping and exposing to view the series of transparent 40 sheaths 31.

45 On the front of the pockets 30, the upper edges of the file cards in a given chain are inserted under the fold 32 of the sheath 31 so that the inscription on the top of the file card can be seen through the transparent fold 32, as shown in Fig. 7. Thus, the file card becomes self-indexing and the fold 32 also holds the upper end of the chain of file cards in position on the pocket 30. In order to hold the bottom end of the chain 50 of cards in position on the pocket 30, ears 40 are cut from the pocket 30 near the strip 35 and the lower end of the chain of file cards is inserted under this ear. A plurality or vertical series of these ears 40 may be provided so that the bottom 55 of the chain of cards will be held in position on the pocket 30 regardless of the length of the chain of cards.

60 In order to attach chains of file cards to the back of the pockets 30 as shown in Fig. 6, slots 60 37B are provided in the pocket adapted to receive the tabs 25 of the top file cards in the chains. The bottom edge of the bottom card of each chain is then slipped under the short fold 65 33 of the transparent sheath 31.

65 The frames 39 are preferably supported in a vertical position in a metal tray or box 41 having angle strips 42 along the inside of each side wall 43. A roll 44 is formed at the bottom of each frame 39 and the end 45 of the roll extends 70 under the angle strip 42, thus permitting the frame 39 to be tilted at a considerable angle but still be retained in the box 41. A hinge member 46 is pivotally mounted on each end 47 of the tray, this hinge member being adapted to en- 75

gage a clip 48 on the end frame 49 when in one position and to be swung outwardly and downwardly into an open position when it is desired to remove frames from the tray 41 or to refer to 5 pockets mounted on frames near the center of the tray 41. The angle strip 42 extends within some distance of the end 47 of the tray 41, thus permitting frames to be removed by sliding toward one end of the tray 41 until the roll ends 45 are cleared from the end of the angle strip 42. In reference to the cards on the back of pockets 38, the pockets are bent forward almost to a horizontal position.

The apparatus for making the photographic 15 file cards 27 consists, in the preferred embodiment of the invention, of a mechanism for winding the sensitized strip 20 with an intermittent motion from a supply spool 50 to a second spool or reel 51. During each dwell in the intermittent 20 movement of the strip 20, the image of the notations on a card or sheet 52 to be copied is photographed onto the strip by mechanism to be hereinafter described. If the cards are to be later attached together in chain form as above 25 described, appropriate punchings 22, 23 and 24 are made in the cards preferably somewhat before the exposure of the image so that the punches serve to position the strip accurately during exposure, as well as provide a means for accurately 30 positioning the strip for cutting the separate cards therefrom.

The intermittent movement of the sensitized strip 20 is accomplished by means of a drive pulley or wheel 53 which is rotatably mounted on 35 shaft 54, the latter being rigidly mounted in bearings 55 of frame member 56. A plurality of radially positioned pins 57 are slidably mounted in holes in the outer rim of the wheel 53 and inner hub portion 58 (Fig. 20). An annular shoulder 59 is formed on each pin 57 and springs 60 between said shoulders and the rim 58 tends to move the pins inwardly toward the axis of the wheel 53 so that the inner ends of the pins always contact with cams 61 fixed by pins 61A to 40 shaft 54. The outer ends of the pins 57 are adapted to enter the punched slots 22 or 23 in the strip 20 when a section 62 (Fig. 10) of the cams 61 having a comparatively large radius causes the pins 57 to move radially outward as the strip 45 20 passes around the lower half of the wheel 53. In order to cause the driving pins 57 to move inwardly and release from the strip without tearing the same, an annular section 63 of the cams 61 of comparatively small diameter, allows the pins 55 to move inwardly.

It is desired to have the intermittent rotation or movement of the wheel 53 start with a slow acceleration under a spring driving impulse so that the strip 20 will not be torn nor damaged in 50 starting its movement. For this purpose, a drive shaft 64 is rotatably mounted in bearings 65 which are formed on frame member 56. A wheel 65a is rigidly secured to shaft 64 by means of pin 66, and a pawl 67 is pivotally mounted on 55 wheel 65 by means of pin 68. One face of wheel 65a is notched out to permit a limited rocking or partial rotation of pawl 67, as seen in Fig. 19. This notch in the wheel 65a forms a stop shoulder 69, against which the upper end 70 of the pawl 67 engages to limit its rotation in a clockwise direction. A spring 71 connects the lower end of pawl 67 to a pin 72 secured to the outer edge of wheel 65a. An annular series of pins 73 extends from one edge of the wheel 53 so that as the pawl 75 67 is rotated by means of shaft 64, it engages

one of these pins 73 at each revolution to cause the wheel 53 to rotate one step of its revolution, thus moving the strip 20 the distance of one file card 27. When the pawl 67 first contacts with pin 73, the spring 71 is extended to give a slow 5 acceleration to wheel 53 until the end 70 of the pawl contacts with the limiting shoulder 69, which causes the partial rotation of the wheel 53 in its step by step intermittent motion. It should be understood that any other suitable means of driving wheel 53 with intermittent driving mechanism may be used.

The reel 51 is preferably enclosed in a light tight removable metal box 74, having a slot 75 near one side of its bottom through which the strip 20 travels as it winds from its reel 50 to reel 51. A strip of felt or other opaque flexible material 76 is fastened to the inside of the bottom of the box 74 and bears against the inside of the strip 20, so that when all of the strip has been 20 unwound from reel 50 to reel 51, the strip 76 will fall down to a horizontal position and close slot 75, so that the metal box 74 may be removed from the case 78 of the photographing apparatus without further exposure of sensitized strip 20 to the 25 light.

It is preferable to keep the strip 20 under a slight tension at times, and for this purpose, the shaft 79 of reel 51 engages a clutch 80 of a spring motor 81 of standard construction. A winding 30 key 82 is provided outside of case 78, so that the motor 81 may be wound at intervals. The end of the shaft 79, opposite spring motor 81, is removably and resiliently held by means of a spring actuated bearing 79A pressing against its end. 35 The reel box 78 is removably secured in casing 78 by angle strap 78A and a pair of hingedly connected plates 83, secured thereto by thumb screws 84 and 85. The bottom of casing 78 is preferably formed of a base 86 of wood or other suitable material, to which metal case 78 is attached by screws 87. A cover 78B is hingedly connected to the top of the case 78 for the purpose of inserting a new reel 50 at intervals. Preferably, a flexible leader strip 20A having hooks 20B for engaging 45 the end of the strip 20, is provided on the reel 51 for convenience in installing a new roll of the strip 20.

An arm 88 is pivotally connected on the base 86 by means of pin 89, and roller 90 is rotatably 50 mounted on the end of arm 88 by means of pin 91, so that the strip 20 travels at all times between the outer periphery of wheel 53 and that of roller 90. The roller 90 is maintained resiliently in contact with the strip 20 by means of a 55 spring 92 connected to arm 88 and to a shoulder 93 secured to base 86.

When all of strip 20 has been unwound from the reel 50 to reel 51, it is desirable to have an automatic signalling device which will indicate 60 on the outside of case 78 the condition of the strip. This is actuated by a bell crank lever 94, pivotally mounted on pin 95 and having roller 96 rotatably mounted on the end of one of its arms by means of pin 97. This bell crank lever 94 is 65 so mounted that gravity tends to maintain the roller 96 in contact with strip roll 20 at all times. The other arm 98 of said bell crank lever 94 has an upstanding shoulder 99 on its end, which is adapted when the bell crank lever is in its lower- 70 most extreme position, to engage in an electric switch member 100 which closes an electrical circuit of standard construction not shown, thus operating a signal 101, such as buzzer, light, etc. When this signalling device is actuated, the oper- 75

ator of this photographing machine can then make provisions for supplying a new sensitized roll 21 into the casing 78 and remove the reel 51 containing the exposed strip.

- 5 The preferred embodiment of the invention contemplates the use of a copy holder, into which the material to be photographed, such as library cards, correspondence, etc., can be manually or automatically inserted, and a mechanism to operate this copy holder can be adjusted to automatically make any desired number of photographed copies of the desired card or memorandum. In the preferred form, this copy holder consists of a plurality of radially extending arms 102 which are mounted on a hub 103, the latter being secured to a shaft 104 rotatably mounted on bearings 105 on one end of base 86. The cards 52 to be copied can be held on arms 102 in any desired way, such as by spring clips 105a so that when 10 the copy holder is rotated automatically, by a mechanism to be hereinafter described, into focus position with one arm 102, in a horizontal plane under a photograph lens tube 106, the card will be held rigidly in said horizontal focus plane. 15 The surface of card 52 may be brightly illuminated by means of a plurality of electric lamps 107, which may be mounted in any suitable way, such as on front wall 108 of case 78. By means of these lamps 107, the image of the inscriptions on the card 52 is reflected upwardly into the reflecting prism 109, and then inwardly through tube 110 onto sensitized strip 20. Lens 111 is interposed between reflecting prism 109 and the sensitized strip 20, so that the image is properly focused 20 when it falls upon the sensitized strip.
- 25 It is desirable to interpose a shutter mechanism between the tube 110 and the sensitized strip, so that no light will get to the sensitized strip when the latter is in motion. For this purpose, 30 a circular shutter 112 is provided with a pair of semicircular openings 113, the ends of these openings being spaced apart by solid segments 114, which serve to close the tube 110 while the strip 20 is in motion. When the movement of 35 the strip 20 is stopped, the rotation of shutter 112 is so timed that these openings 113 come opposite tube 110, thus allowing the light and image of card 52, to pass through said opening onto the sensitized strip. The shutter 112 is 40 secured to stud 115, which in turn is rotatably mounted in a bearing 116, this bearing being part of a bearing bracket 117 secured in a suitable manner to the frame member 56. The outer periphery of the shutter 112 is provided with 45 gear teeth 112' adapted to mesh with and be driven by similar gear teeth 118' on the outer periphery of gear 118 (see Fig. 12). The gear 118 (Figs. 11 and 12) is rigidly secured to shaft 119, the opposite end of said shaft being provided 50 with bevel gear 120, which meshes with another bevel 121 secured to the end of drive shaft 64. The shaft 119 (Fig. 11) is rotatably mounted at one end in bearing 122 on bracket 117, and at 55 the other end in bearing 123 secured to frame member 56. Each end of shaft 64 has a clutch 124 which extends through a hole in case 78, so that a source of energy, such as an electric motor, may be attached to the drive shaft through one of said clutches 124. Also several of these 60 photographing machines may be assembled together through clutches 124, so that a number of these machines may be operated from a single motor, and all of the machines will be in a line convenient for operation.
- 65 A mechanism is provided for moving the copy

holder arms 102 through part of a revolution while the sensitized strip 20 is moved. This mechanism consists of a reciprocating rod 125 (Fig. 10), which is slidably mounted in frame member 56, shoulder 93, and the front wall 108 of 5 the case 78. An upstanding flange 126 is secured to rod 125 adjacent wheel 53 (Fig. 15). This flange 126 is in the path of travel of pins 13 so that, when wheel 53 is rotated through part of a revolution, one of the pins 13 engages 10 said flange 126, and moves rod 125 to the left against the action of a spring 127 on the rod 125 between shoulder 93 and annular shoulder 128 formed on said rod. This motion to the left of rod 125, as seen in Fig. 10, causes a downwardly 15 extending, pivotally mounted tooth 129 to engage one of a plurality of pins 130 on hub 103 so as to cause the rotation of the copy holder through part of a revolution, thus bringing another arm 102 containing another card to be copied, into 20 position and into focus. As the pin 13 engaging flange 126 again starts to move upwardly through its circular path, it disengages from flange 126 and rod 125 then snaps to the right under the action of spring 127. Any other mechanism for 25 causing a partial rotation of copy holder as the strip 20 moves, or any mechanism which will move the cards to be copied into and out of the focus or photographic position, may be used instead of the mechanism described. 30

It is preferable to so control the movement of the rod 125 that one or any number of photographic copies of a given card may be made automatically. For this purpose a series of outstanding studs 131 (Figs. 15 and 16) are radially attached to the outer edge of the wheel 53, and a second series of studs 132 are also secured to the outer periphery of wheel 53, the two series of studs 131 and 132 lying in a plane perpendicular to the axis of wheel 53, these planes being spaced 40 apart a predetermined distance so that each series of studs selectively actuates the copy holder control mechanism to be hereinafter described.

This copy holder control mechanism preferably consists of a bell crank lever 133, rigidly mounted 45 on shaft 134 (Fig. 16). One arm 133A of this lever 133, is pivotally attached by means of pin 135, to a lever 136. A spring 137 is attached to the end of lever 136 opposite pin 135, and said spring is also attached to a pin 138 fastened 50 to the inside of case 78. A shoulder 139 is formed on the rear face of lever 136, said shoulder being so positioned that it will move into and out of the path of rotation of pins 131 and 132 as the shaft 134 is rocked. A rod 140 is pivotally connected to the end of lever 136 adjacent the spring 137, and said rod hangs downwardly and passes through an opening or bearing 141 in the base 86. An annular shoulder 142 is formed on rod 140, said shoulder being so positioned that, as the 60 rod 140 is moved downwardly by lever 136, said shoulder will engage one arm 143 of a trip lever 144. This trip lever is pivotally mounted on a fixed pin 145, secured to an angle bracket 146. A second arm 147 of the lever 144 is normally 65 held in the path of travel of an annular shoulder 148, formed on the rod 125. A rod 149 is pivotally connected at one end to pin 150 on a second arm 151 of the bell crank lever 133. The opposite end of the rod 149 passes through, and 70 is slidably supported by, bearing plate 152, secured to the outer wall of case 78. A cam 153 is formed on the rod 149 so that when rod 149 is moved axially to the right by the bell crank lever 133, said cam engages arm 143, of lever 144 (Figs. 75

15 and 16), thus pressing down said arm 148 and holding the arm 147 out of the path of travel of the shoulder 148.

The shaft 134 passes through the front wall 108 of the case and adjusting lever 154 (Figs. 10, 15, and 18) is secured to the outer end of shaft 134, said adjusting lever having a handle 155 so that it may be manually actuated. The outer end of the lever 154 has a notch or fork 156 and said lever 154 is slightly flexible. A series of pins 157 is positioned in the wall 108 in the path of the fork 156 so that the lever 154 can be pulled outwardly and dropped over one of the pins 157 to adjust the copy holder mechanism in a position where the number of copies to be made of each card is determined. As shown in Fig. 18, the left hand position indicates that one copy of a card will be made and the second position, indicated by the letter "R", indicates that an indefinite number of copies will be made of each card. A third position to the right, indicated by the numeral "4", indicates that four copies will be made of each card, and in the same way, the last position to the right indicates that two copies of each card will be made. When the lever 154 is in a position for making one copy of each card, the lever 136 is in its farthestmost left hand position where the shoulder 139 will not engage with either of the series of pins 131 and 132, and in this position, cam 158 also holds the lever arm 147 out of engagement with shoulder 148. When the lever 154 is in position marked "R", cam 158 is disengaged from arm 148, but shoulder 139 does not engage with the two series of pins 131 and 132. When lever 154 is in position marked "4", shoulder 139 engages series of pins 132, these pins being two in number, and positioned diametrically opposite on the outer periphery of the wheel 53. Thus, in this position, the lever 136, rod 140, and lever 144 will be actuated twice for every revolution of the wheel 53 to make four duplicate copies of the file card exposed, since one complete revolution of the wheel 53 means the exposure of eight file cards. When the lever 154 is in the position marked "2", the shoulder 139 will be engaged by both series of pins 131 and 132 so that lever 136, rod 140 and lever 144 will be actuated for every other card exposed. Any other mechanism which will operate to regulate the number of exposures to be made for each card, may be used in place of the mechanism described.

In order to position the copy holder arms 102 accurately in focus, a stop bar 158 is slidably mounted on the base 86, so that when the bar 158 is in its farthestmost right hand position, as shown in Fig. 10, the end of the copy arm 52, which is in focus position, will rest against the end of said stop bar 158. A latch 159 is pivotally mounted on pin 160 secured to bracket 161 on wall 108, said latch having a spring 162 connecting its upper end to the wall 108 so that the latch 159 is continually urged in a counter clockwise direction by said spring. As the copy holder arm 102 is rotated through part of a revolution, the arm first engages the resiliently held cam surface 163 of latch 159, which retards the rotation of the copy holder and prevents too sudden a jarring stop against the stop bar 158.

In order to release the copy holder arm 102 after exposure of the card, a pair of upstanding shoulders 164 (Fig. 10) is formed on the inner end of the stop bar 158. A cam lever 165 (Figs. 10 and 17) is pivotally mounted on pin 166 secured to angle bracket 167, the latter being fastened to the base 86. The bottom of the lever 165 has a

downwardly extending finger 168 which lies between the upstanding shoulders 164 on stop bar 158. A spring 168A connects the lever 165 to the inner side of the front case wall 108, so as to normally urge the stop bar 158 to the right as seen in Fig. 10. The lever 165 has an inwardly extending flange 169 (Fig. 17) which normally lies in the path of travel of a trigger catch 170 formed on a trigger 171. This trigger is pivotally mounted in a slot which extends through rod 125, the pivot for said trigger being formed by pin 172. A spring 173 connects an arm 174 on one end of trigger 171 to a pin 175 on the rod 125, so as to urge the trigger in a counter clockwise direction as seen in Fig. 17, with a shoulder 176 on said trigger acting to limit the rotation thereto. Thus when the rod 125 is moved to the left, as seen in Fig. 10, by the flange 126, the trigger catch 170 will engage flange 169 so as to move the lever 165 rearwardly or to the left as shown in Figs. 10 and 17, so and cause the stop bar 158 to release the copy holder arm 102 and permit the rotation of the copy holder under the action of tooth 128.

While the sensitized strip 20 is held stationary during the exposure, it is desirable but not essential to punch the perforations 22, 23 and 24 into the strip, the punches also serving to hold the strip stationary during exposure. This punching mechanism is formed of a punch block 177 (Fig. 13) into which are inserted suitably shaped punches 22A, 23A and 24A which register with similarly shaped openings in a die block member 178. Guide pins 179 are secured to the die block 178 and are slidably mounted in similarly shaped openings in the punch block 177, these guide pins 179 serve to cause the punches to register exactly with the openings in the die block 178. A pair of angle clips 180 is secured to punch block 177 by any suitable means, such as bolts 181 and eccentric connecting rod 182 is pivotally mounted between angle clips 180 on pin 183. An eccentric 184 is secured to shaft 64 and said eccentric is adapted to fit into an opening in eccentric strap 182. Thus the punches are moved into and out of the die block 178 for every rotation of shaft 64 as the strip 20 is held in stationary position. The die block is also formed with an exposure opening defining the portion of the strip 20 on which a card is photographed, this opening being in alignment with the tube 110.

It is preferable to position a pair of tension rolls 185 above punch 177, these rolls being positioned one on each side of strip 20, and being rotatably mounted on bracket 186 secured to frame member 56. These rolls serve to keep the strip perfectly flat adjacent the punches during the punching and exposing operation. An important result obtained by punching the strip 20 at the position and substantially simultaneous with exposure to receive and record the image of a record card or other matter, is the fixing of the image on the strip with the opening punched therein in a predetermined relation. This occurs in each punching and photographing operation, and by which cards may be subsequently cut from the strip in a very accurate manner by using the punched openings for controlling the position of the strip in a cutting mechanism so that in the cutting of the strip to form the card, the image of the card may be accurately cut from the strip by the controlling action of the openings and the mechanism in securing this positioning.

In operation the web 20 unwinds from reel 52, passes around drive wheel 53 and then winds onto reel 51, the strip being kept under slight tension 73

by spring motor 81. Pins 57 are moved outwardly under the action of cam section 62 to engage slots 22 and 23 in the strip 20, and cause said strip to be moved by the wheel 53. The card to be photographed is placed on the copy holder arm 102 under spring clips 105, and the copy holder arm is then rotated under the action of tooth 129 into a position where arm 102 snaps into focus position between the stop bar 158 and the latch 159. In this position the card 52 is illuminated by lamps 107, the reflected image passing up through reflecting prism 109, lens 111, tube 110, shutter opening 113 onto the sensitized strip 20, where the strip is exposed with the image of the inscriptions 28 on the card 52 to be photographed through the opening in die block 178.

The rotation of drive shaft 64 now causes the outer end of the resiliently held pawl 61 to engage one of pins 73 and rotate the wheel 53 through part of a revolution, equal to the length of one of the photographic file cards, to the next exposure position. This movement of wheel 53 causes one of pins 73 to engage flange 126 and slide the rod 125 to the left, as seen in Fig. 10, against the action of spring 127. This movement of rod 125 causes tooth 129 to engage another pin 130 and move another copy holder arm 102 into position between latch 159 and stop bar 158. This movement of rod 125 to the left also causes trigger catch 170 to engage flange 169 on lever 165 so that finger 168 engages shoulder 164 and moves stop bar 158 to the left so as to release it from the end of the arm 102 and permit the rotation of the copy holder to a new focus position. After the pin 73, engaging the flange 126, is disengaged by said flange due to continued rotation of the wheel 53, tooth 129 rotates about its pivot and slides over pin 130, while finger 168 pushes the shoulder 164 and bar 158 to the right as seen in Fig. 10, under the action of spring 168A.

The shutter 112 is geared through teeth 116, to gear 118 mounted on shaft 119, said shaft being driven through bevel gears 120 and 121, the latter gear being on drive shaft 64. This shutter is so timed that one of the openings 113 will be adjacent the tube 110 when the strip 20 is stopped for an exposure during a dwell in the intermittent motion of wheel 53. While the strip 20 is stopped for an exposure, the punches 22A, 23A and 24A punch the slots 22, 23, and 24 in the strip, these punches also serving to hold the strip rigidly in position during exposure and so that the slots and photographic image on the strip are in a fixed relation to each other. The punch 177 is actuated from drive shaft 64 by eccentric 184, through eccentric connecting rod 182.

The numbers of exposures or copies to be made of a particular card is regulated by adjusting the lever 154 to any one of the four positions shown in Fig. 18. When in position 1, the cam 153 holds down lever arm 143 so that arm 147 does not engage shoulder 148, with the result that the copy holder arms 102 are rotated with a new card for every exposure, and only one copy is made of each card. If the lever 154 is in position "R", cam 153 is out of engagement with lever arm 143 and rod 125 is held permanently to the left, as seen in Fig. 15, through the engagement of lever arm 147 with shoulder 148, so that an indefinite number of exposures of each card results, as the copy holder arms 102 are not rotated with each exposure. When the lever 154 is in position "4", shoulder 139 on lever 136 engages a series of pins 132, thus causing the lever 136 to be moved down-

wardly for each pin engagement. This downward movement of the lever 136 also moves rod 140 downwardly, and causes the shoulder 142 to trip the lever arm 143, thus disengaging the lever arm 147 from the shoulder 148, so that tooth 129 moves the copy holder arm into focus position with a new card. The pins 132 are so positioned that this movement of the copy holder will take place after four exposures of photographs are made of each of the cards 52. When arm 154 is in position "2" as seen in Fig. 18, the shoulder 139 will engage both series of pins 131 and 132, and in a manner described in a previous paragraph, the copy holder will be rotated so as to bring a new card into position for every two exposures.

When the roll 21 is completely unwound from reel 50, lever 94 moves downwardly, causing the shoulder 99 to close electric switch 100 and actuate audible or visible signal 101 to indicate that it is necessary to replenish sensitized strip 20. The metal box 74 is then removed from the photographing case after disconnecting the hingedly connected plates 83, and the strip is developed in the usual way and dried. The resulting strip, as shown in Fig. 3, is then cut into cards 27 by severing the strip across dotted lines 26. These cards 27 are then fastened together in the form of a chain or series 29 by inserting tabs 25 in slots 22 or 23. These chains of cards can then be inserted into file pockets 30 by slipping the bottom of the card chain under ear 40, and the top of the card under fold 32. Out-standing tongues 31 of strips 35 are then inserted under angle strips 38 of each file frame, so as to form a series of overlapping pockets. The roll ends 45 at the bottom of each frame 39, can then be inserted under angle strip 42 of file tray 41, and the photographic file cards in chain form can be referred to at any time.

I would state in conclusion that while the illustrated examples constitute a practical embodiment of my invention, I do not limit myself precisely to the details herein described, since manifestly the same can be considerably modified without departing from the spirit of the invention as defined in the appended claims.

What is claimed is:—

1. A method of duplicating records, consisting in taking a series of discrete documents and successively placing each document in a photographing position, directly and successively photographing positive images of each document from the document, onto successive portions of a sensitized paper strip, marking said paper strip adjacent each side thereof substantially simultaneously with the photographing of each document to provide gauge marks fixed with respect to the photographic image of the document, developing, fixing, washing and drying said strip, and subsequently severing each photograph on all sides from said strip to an exact size using said marking as a gauging means to control the position of the photographic image relative to the edges of the strip both longitudinally and laterally, whereby the severed part of the strip having the photograph may be brought into registry to produce a uniform duplicate discrete record in which a series of duplicate discrete records may be produced that have an accurate uniform size.

2. A method of duplicating records, consisting in taking a series of discrete documents and successively placing each document in a photographing position, directly and successively photographing positive images of each document onto

successive portions of a sensitized paper strip, punching openings in said strip adjacent opposite sides substantially simultaneous with the photographing of each record to provide gauging means fixed with respect to the photographic image, developing, fixing, washing and drying said strip, and subsequently severing each photograph on all sides from said strip to an exact

size using said punch openings as a gauge means to control the position of the severing relative to the strip whereby the severed portion of the strip and the photograph on the strip may be registered to produce a uniform duplicate discrete record.

LE ROI E. HUTCHINGS. 5
